(57) **CLAIM**

The ornamental design for a hooded sweatshirt, as shown and described.

DESCRIPTION

FIG. 1 is a perspective front view of a hooded sweatshirt showing my new design;

FIG. 2 is a perspective rear view thereof;

FIG. 3 is a front view thereof;

FIG. 4 is a rear view thereof;

FIG. 5 is a left side elevational view thereof;

FIG. 6 is a right side elevational view thereof;

FIG. 7 is a rear elevational view thereof; and,

FIG. 8 is a front elevational view thereof.

The broken lines depict portions of the hooded sweatshirt that form no part of the claimed design. The broken lines showing the drawstrings, seams, and stitching form no part of the claim.

1 Claim, 8 Drawing Sheets
